WASHING MACHINE

Herbert F. Bariffi, Hamden, Conn., assignor to
General Electric Company, a corporation of
New York

Application January 31, 1936, Serial No. 61,664

12 Claims. (Cl. 68—23)

The present invention relates to washing machines of the type having a centrifugal extractor for drying the clothes.

The object of my invention is to provide an improved construction and arrangement in washing machines of this type, and for a consideration of what I believe to be novel and my invention attention is directed to the following description and the claims appended thereto.

0 In the accompanying drawing, Fig. 1 is an elevation partly in section of a washing machine embodying my invention; Fig. 2 is an enlarged view of the driving connections for the agitator and the rotatable receptacle as shown in Fig. 1; 5 Fig. 3 is a sectional view taken on line 3—3 of Fig. 2; and Fig. 4 is an enlarged fragmentary view of the guide bearing for the vertical shaft.

Referring to the drawing, the washing machine comprises a stationary tub 1 which is supported 20 on a base 2. The upper end of the tub is partially closed by an annular cover 3 having a flange 4 which fits within the upper edge of the tub. Between the flange 4 and the tub is a suitable gasket 5. A cover 6 rests on the inner edge 25 of the annular cover 3 and completes the closing of the top of the stationary tub. When clothes are to be inserted or removed from the washing machine, only the cover 6 need be removed. The cover 3 is removed when the inside of the 30 stationary tub is to be cleaned. The base 2 is provided with a skirt 7 which extends above the bottom of the stationary tub and covers the abutting edges of the tub and the base.

Within the base 2 is supported a driving mechanism for the washing machine which is adapted 35 to effect selective oscillation or rotation of a vertical shaft 8. Any suitable driving mechanism may be used, for example, the driving mechanism shown in application, S. N. 14,255, filed April 2, 1935. Keyed to the shaft 8 is a brake drum 9. The brake drum 9 is connected by means of a universal joint to the lower end of a vertical shaft 10 which extends through a sleeve 11. The universal joint comprises diametrically opposed 45 pins 12 which are fixed in ears 13 on the upper side of the brake drum. The inner ends of the pins 12 are journaled in bearings 14 clamped between plates 15 which form the intermediate member of the universal joint. The lower end 50 of the shaft 10 is provided with diametrically opposed pins 16 which are spaced between the pins 12 and are likewise journaled in bearings carried between the plates 15. With this construction, the vertical shaft 10 may have a gyroscopic movement with respect to the driving shaft 8.

The sleeve 11 extends above the normal water level in the stationary tub 1. The upper end of the sleeve is provided with a spherical seat for a self-lubricating sleeve bearing 17 which guides the vertical shaft 10. This spherical seat, which is more clearly shown in Fig. 4, comprises a flared portion 18 of the sleeve and a collar 19 which is threaded into the upper end of the sleeve. This spherical seat permits alignment of the bearing 17 with the shaft 10 so that the bearing pressure is uniform regardless of the inclination of the shaft.

The housing for the driving mechanism which is supported within the base 2 has a hollow post 20 which extends through central openings in the top wall of the base and the bottom wall of the stationary tub. The post 20 is secured to the bottom wall of the tub and to the base by means of screws 21 which are threaded through a clamping ring 22 into a flange 23 which is integral with the post 20. Suitable gaskets are arranged between the flange 23 and the base and between the base and the bottom wall of the tub. Leakage from the bottom of the tub is prevented by means of a rubber sleeve 24 which has its lower edge clamped between the ring 22 and the bottom of the tub and which has its upper edge clamped to the sleeve 11 above the post 20 by means of a clamp 25. Within the post 20 is a resilient mounting for the lower end of the sleeve 11 which comprises two annuluses 26 of rubber or other resilient material. The lower annulus is arranged between an inwardly extending flange 27 at the lower end of the post 20 and a flange 28 projecting from a sleeve 29 secured to the sleeve 11. The upper annulus is arranged between the upper side of the flange 28 and a washer 30. The inner edge of the upper annulus 26 rests against a sleeve 31 which is fixed to the sleeve 11. The sleeve 31 is of the same dimensions as the sleeve 29 and is used so that the annuluses 26 may be of the same size. The resilience of the mounting is adjusted by means of a nut 32 which is threaded into the upper end of the post 20. This nut varies the compression of the rubber and thereby varies the stiffness of the mounting. With this mounting, the sleeve 11 is resiliently held in a central position and is free to tilt in all directions in order that the shaft 10, which is guided in the sleeve, may have a gyroscopic movement.

In the upper part of the stationary tub is a rotatable tub or receptacle 33 for receiving liquid and material to be washed. The space between the bottom of the receptacle 33 and the bottom of the stationary tub 1 is sufficient to provide a

storage space for all the liquid which can be placed in the receptacle. At the center of the receptacle is a vertical sleeve 34 which serves as the hub for the receptacle. The upper end of the sleeve 34 projects above the water level in the receptacle. The lower end of the sleeve 34 fits into an opening in the bottom wall of the receptacle and an opening in a stiffening disk 35, both of which are held in position between a shoulder and a spun-over portion, as shown at 36. The lower end of the sleeve 34 is provided with a circular flange 37 which extends over the upper side of the bottom wall of the receptacle. The flange 37 and the stiffening disk 35 are secured to the bottom wall of the receptacle by means of rivets 38. The lower end of the sleeve 34 is guided by a self-lubricating bearing 39 which is fixed either to the vertical shaft 10 or to the sleeve 34. The upper end of the sleeve 34 is guided on the shaft 10 by a self-lubricating sleeve bearing 40 which is pressed within the upper end of the sleeve against an inwardly extending flange 41 formed thereon. The lower end of the sleeve bearing 40 bears on a hardened steel thrust collar 42 which is keyed to the shaft 10. The thrust collar is supported on the shaft by means of a shoulder 43 on the shaft. The weight of the receptacle and the material contained therein is transmitted to the thrust collar 42 by the bearing 40 and through the shoulder 43 to the shaft 10. From the shaft 10 the weight is transmitted through the universal joint and the shaft 8 to a suitable thrust bearing in the driving mechanism which is contained within the base 2. When the covers 3 and 6 are removed, the receptacles may be lifted from the shaft.

The shaft 10 projects above the sleeve 34 and the projecting end is provided with splines 44 which fit between complementary splines formed in a bushing 45 which is fixed in the upper end of the hub of an agitator 46. Leakage of water through the upper end of the agitator as the water is splashed about is prevented by a cup 47 which is snapped in placed over the upper end of the agitator. The splines 44 provide a rigid driving connection for the agitator and at the same time permit the agitator to be easily lifted from the end of the shaft.

During washing, the shaft 10 is oscillated through the driving shaft 8 and thereby causes oscillation of the agitator 46 in the receptacle 33. During this oscillation of the agitator the receptacle remains substantially stationary due to inertia. The clothes are prevented from falling over the upper edge of the receptacle by means of an annular guard ring 48 which is located slightly below the upper edge of the receptacle. During washing, water may be continuously discharged into the top of the receptacle. The excess water will flow through openings 49 in the guard ring over the upper edge of the receptacle, carrying with it the scum which floats on top of the water. The inner edge of the guard ring 48 is provided with a vertical flange 50 having a rounded upper edge 51 which serves as a handle by means of which the receptacle may be lifted from the shaft 10.

During extracting, the driving connection between the shaft 10 and the receptacle 33 is effected by means of a centrifugal clutch which is carried on the thrust collar 42. This clutch comprises two shoes 52 which are held against a squared cam surface 53 of the thrust collar by means of two split rings 54. During washing, the agitator 46 is oscillated and the oscillation of the

shaft 10 is at a relatively slow speed of the order of magnitude of 60 oscillations per minute, and the split rings 54 are strong enough to hold the shoes 52 against the squared portion 53.

For wringing, the shafts 8 and 10 are rotated and as soon as the speed of rotation of the shaft 8 exceeds a few hundred R. P. M. the clutch shoes 52 move outwardly under the action of centrifugal force and touch the inner surface of the sleeve 34 which forms the hub of the receptacle 33. As soon as the shoes 52 contact the inner surface of the sleeve 34, their rotation is retarded and the squared surface 53 of the collar 42 co-operates with the inner surface of the shoes 52 and wedges the shoes tightly against the inner surface of the sleeve 34. This effects a positive driving connection between the shaft 10 and the receptacle which causes the receptacle to be rotated. Similarly, when the speed of the shaft is retarded by a brake in stopping, the shoes release and wedge in the opposite direction.

This clutch construction and the provision of a self-aligning bearing for guiding the vertical shaft 10 is not my invention, but is the invention of George W. Dunham and is claimed in his application Serial No. 61,635, filed Jan. 31, 1936.

In the use of the machine the receptacle 33 is loaded with clothes and filled with a suitable washing solution. The driving mechanism is then adjusted so that the shaft 10 is oscillated. During this oscillating movement the receptacle 33 remains substantially stationary due to inertia and the oscillation of the agitator relative to the receptacle causes the clothes to be washed. During the washing operation, the receptacle 33 will probably be tilted to one side due to the fact that the clothes are not uniformly distributed in the receptacle. This inclination is permitted by the resilient support for the lower end of the sleeve 11 and by the universal joint arranged between the driving shaft 8 and the lower end of the shaft 10. Water is preferably continuously discharged into the top of the receptacle 33 and allowed to flow continuously over the upper edge of the receptacle, thereby floating off the scum which collects on the top of the water. During the washing operation the bearing loss in the bearings 39 and 40 is negligible due to the low speed of oscillation of the shaft 10.

At the conclusion of the washing operation, the driving mechanism is adjusted so that the shaft 8 is rotated continuously in one direction. As soon as the speed of rotation of the shaft 8 exceeds a few hundred R. P. M. the clutch shoes 52 move outwardly under the action of centrifugal force and touch the inner surface of the sleeve 34 which forms the hub of the receptacle 33. As soon as the shoes 52 contact the inner surface of the sleeve 34, their rotation is retarded and the squared surface 53 of the collar 42 co-operates with the inner surface of the shoes 52 and wedges the shoes tightly against the inner surface of the sleeve 34. This effects a positive driving connection between the shaft 10 and the receptacle which causes the receptacle to be rotated.

Since the clothes may be nonuniformly distributed in the receptacle, the receptacle may be unbalanced. This unbalance will usually consist partially of a static unbalance which is equivalent to a single weight displaced from the axis of rotation of the receptacle and partially of dynamic unbalance which is equivalent to the couple produced by the weights of equal size 70-75

cated in different planes on opposite sides of and equidistant from the axis of rotation of the receptacle. The static unbalance will tend to cause gyration of the receptacle about its axis so that the receptacle rotates about its center of mass. The dynamic unbalance will tend to cause tilting of the receptacle so as to bring the receptacle into a position in which there is no unbalanced couple. The resilient mounting provided for the lower end of the sleeve 11 permits gyration of the receptacle about its axis so that the receptacle rotates nearly about its center of mass, thus neutralizing the effect of static unbalance. Since the resilient mounting has some stiffness, the gyration of the receptacle about its axis is not sufficient to permit the receptacle to rotate about its center of mass but the resilient mounting does permit sufficient gyration of the receptacle so that the vibration due to static unbalance is considerably decreased. However, the sleeve bearings 39 and 40 prevent tilting of the receptacle with respect to the shaft 10 and the receptacle will therefore cause vibration due to the dynamic unbalance. This tendency of the receptacle to tilt causes heavy bearing pressure on the bearings 39 and 40, but since there is no relative rotation between the bearing surfaces of these bearings, this pressure causes no bearing loss. Most of the force due to the dynamic unbalance of the receptacle will be transmitted through the universal joint at the lower end of the shaft 10 to the shaft 8. This force is taken by the bearings in which the shaft 8 rotates. Since the bearings for the shaft 8 are a considerable distance from the receptacle 33, the force on the bearings due to the unbalanced couple is less than it would be at a point nearer the receptacle. This means that the bearing loss due to the unbalanced couple is decreased. Also, these bearings are located below the stationary tub 1 and are therefore not subjected to the humid atmosphere within the tub and more easily lubricated. Some of the force due to the dynamic unbalance or unbalanced couple is transmitted to the sleeve 11. However, since this sleeve is resiliently supported these vibrations are cushioned. The cushioning action decreases the bearing pressure on the bearing 17 and thereby decreases the bearing loss.

In previous constructions the receptacle has been supported on a sleeve surrounding the driving shaft by means of a thrust bearing between the receptacle and the upper end of the sleeve and the lower end of the receptacle has been guided on the sleeve by means of a sleeve bearing between the receptacle and the sleeve. With this construction, the thrust bearing has had to be large enough to withstand the bearing loads resulting from high speed rotation of the receptacle and the tendency of the receptacle to tilt due to dynamic unbalance has resulted in heavy bearing pressures between the sleeve bearing between the lower end of the receptacle and the guiding sleeve for the vertical shaft. Due to the heavy pressures, the bearing losses in this bearing have been large and in some cases have amounted to more than one-quarter of the total power required to rotate the receptacle.

In the present construction during extracting, there is no relative rotation between the bearing surfaces of the thrust bearing 40 which supports the receptacle on the shaft or between the bearing surfaces of the sleeve bearing 39 which guides the lower end of the receptacle on the shaft. There is therefore no bearing loss in these bearings during extracting. Also, due to the re-

sistant support for the sleeve 11 the bearing pressures on the bearing 17 are reduced with the result of decrease in bearing loss.

Since the sleeve 11 is resiliently supported at a point spaced from the universal joint through which the shaft 10 is driven, the gyrating movement of the shaft 10 causes the sleeve bearing 17 to turn in its spherical seat in order to provide uniform bearing pressure. If some means were not provided for permitting the sleeve bearing 17 to align itself with the shaft 10, the gyrating movement of the shaft would cause nonuniform bearing pressures.

At the conclusion of the extracting operation the power supplied to the driving mechanism is cut off and rotation of the receptacle is retarded, for example, by a braking force applied to the brake drum 9. When this braking force is applied, the receptacle 33 tends to rotate faster than the shaft 10. This causes the shoes 52 to be rotated in the opposite direction relative to the squared surface 53 and to be wedged between this surface and the inner surface of the sleeve. The force with which the shoes 52 are wedged against the inner surface of the sleeve 34 is proportional to the torque which is being transmitted through the clutch shoes. When the rotation of the receptacle is completely retarded there is no torque being transmitted through the clutch shoes and the clutch shoes may be easily returned to the neutral position by turning the receptacle or the shaft 10 in the reverse direction.

What I claim as new and desire to secure by Letters Patent of the United States is:

1. In a washing machine, a vertical shaft, a receptacle for receiving liquid and material to be washed, a thrust bearing for supporting said receptacle on said shaft in rotatable relation thereto, a guide bearing between said receptacle and said shaft, said bearings being spaced apart along the shaft sufficiently to prevent tilting of the receptacle with reference to the shaft, an agitator in said receptacle, a driving connection between the agitator and the shaft whereby the agitator is oscillated in the receptacle upon oscillation of the shaft, a driving connection between the receptacle and the shaft whereby the receptacle is rotated to extract liquid from the material contained therein upon rotation of the shaft, and means for resiliently supporting the shaft for gyratory movement during extracting whereby the receptacle may rotate about its center of mass.

2. In a washing machine, a vertical shaft, a receptacle for receiving liquid and material to be washed having a hub surrounding said shaft, a thrust bearing at the upper end of said hub above the center of gravity of the receptacle for supporting the receptacle on said shaft in rotatable relation thereto, a guide bearing below the center of gravity of the receptacle between said hub and said shaft, an agitator in said receptacle, a driving connection between the agitator and the shaft whereby the agitator is oscillated in the receptacle upon oscillation of the shaft, a driving connection between the receptacle and the shaft whereby the receptacle is rotated to extract liquid from the material contained therein upon rotation of the shaft, and means for resiliently supporting the shaft for gyratory movement during extracting whereby the receptacle may rotate about its center of mass.

3. In a washing machine, a vertical shaft, means for resiliently supporting said shaft for gyratory movement, a receptacle for receiving

- liquid and material to be washed, a thrust bearing for supporting said receptacle on said shaft in rotatable relation thereto, a guide bearing between said receptacle and said shaft and spaced from said thrust bearing sufficiently to prevent tilting of the receptacle with reference to the shaft, an agitator in said receptacle, a driving connection between the agitator and the shaft whereby the agitator is rotatable by the shaft relative to the receptacle for washing, and a driving connection between the receptacle and the shaft whereby the receptacle is rotatable by the shaft to extract liquid from the material contained therein.
4. In a washing machine, a vertical shaft, means including a sleeve surrounding said shaft for guiding said shaft and for resiliently supporting said shaft for gyratory movement, a thrust bearing for supporting said receptacle on said shaft in rotatable relation thereto, a guide bearing between said receptacle and said shaft and spaced from said thrust bearing sufficiently to prevent tilting of the receptacle with reference to the shaft, a driving connection between the agitator and the shaft whereby the agitator is oscillated in the receptacle upon oscillation of the shaft, and a driving connection between the receptacle and the shaft whereby the receptacle is rotated to extract liquid from the material contained therein upon rotation of the shaft.
5. In a washing machine, a vertical shaft, a receptacle for receiving liquid and material to be washed, a thrust bearing for supporting said receptacle on said shaft in rotatable relation thereto, a guide bearing between said shaft and said receptacle, said bearings being spaced apart along the shaft sufficiently to prevent tilting of the receptacle with reference to the shaft, means operable by said shaft for agitating the material and liquid in said receptacle, a driving connection between said receptacle and said shaft whereby said receptacle is rotatable to extract liquid from the material contained therein upon rotation of said shaft, and means for resiliently supporting the shaft for gyratory movement during extracting whereby the receptacle may rotate about its center of mass.
6. In a washing machine, a vertical shaft, means for resiliently supporting said shaft for gyratory movement, a receptacle for receiving liquid and material to be washed, a thrust bearing above the center of gravity of the receptacle for supporting said receptacle on said shaft in rotatable relation thereto, a guide bearing between said shaft and said receptacle below the center of gravity of the receptacle, means operable by said shaft for agitating the material and liquid in said receptacle, and a driving connection between said receptacle and said shaft whereby said receptacle is rotatable to extract liquid from the material contained therein upon rotation of said shaft.
7. In a washing machine, a vertical shaft, a receptacle for receiving liquid and material to be washed, a thrust bearing above the center of gravity of the receptacle for supporting the receptacle on the shaft in rotatable relation thereto, a guide bearing between the receptacle and the shaft below the center of gravity of the receptacle, a washing element in the receptacle, a driving connection between the washing element and the shaft whereby the washing element may be moved relative to the receptacle by the shaft for washing, a driving connection between the shaft and the receptacle whereby the receptacle is rotated to extract liquid from the material contained therein upon rotation of the shaft.
8. In a washing machine, a receptacle for receiving liquid and material to be washed, a vertical shaft, agitating means in the receptacle operable by said shaft to agitate the liquid and material in the receptacle for washing, a driving connection between the receptacle and shaft whereby the receptacle is rotated to extract liquid from the material contained therein, provisions for supporting the receptacle wholly on the shaft during extracting, a driving shaft, a universal joint connecting the shafts, and means for resiliently supporting the vertical shaft for gyratory movement relative to the driving shaft during extracting whereby the receptacle may rotate about its center of mass.
9. In a washing machine, a receptacle for receiving liquid and material to be washed, a vertical shaft, an agitator operable by said shaft for agitating the liquid and material in the receptacle for washing, a driving connection between the receptacle and shaft whereby the receptacle is rotated to extract liquid from the material contained therein, provisions for supporting the receptacle wholly on the shaft during extracting, a driving shaft, a universal joint connecting the shafts, and means including a sleeve surrounding the vertical shaft for resiliently supporting the vertical shaft for gyratory movement relative to the driving shaft, said sleeve including a bearing for the vertical shaft and being out of contact with the receptacle.
10. In a washing machine, a receptacle for receiving material to be washed, a vertical shaft extending through the bottom of the receptacle, an agitator in the receptacle operable by rotation of the shaft relative to the receptacle, a driving connection between the receptacle and shaft whereby the receptacle is rotatable to extract liquid from the material contained therein, provisions for supporting the receptacle wholly on the shaft during extracting, a driving shaft at the lower end of the vertical shaft, a universal joint connecting the shafts, and means out of contact with the receptacle during extracting for resiliently supporting the vertical shaft for gyratory movement relative to the driving shaft.
11. In a washing machine, a receptacle for receiving material to be washed, a vertical shaft extending through the bottom of the receptacle, an agitator in the receptacle operable by oscillation of the shaft relative to the receptacle, a driving connection between the receptacle and shaft whereby the receptacle is rotated to extract liquid from the material contained therein, provisions for supporting the receptacle wholly on the shaft during extracting, a driving shaft at the lower end of the vertical shaft, a universal joint connecting the shafts, and means for resiliently supporting the vertical shaft for gyratory movement relative to the driving shaft during extracting whereby the receptacle may rotate about its center of mass.
12. In a washing machine, a receptacle for receiving material to be washed, a vertical shaft extending through the bottom of the receptacle, bearing means supporting the receptacle wholly on the shaft in rotatable relation thereto, a washing element in the receptacle operable by rotation of the shaft relative to the receptacle, a

driving connection between the receptacle and shaft whereby the receptacle is rotated to extract liquid from the material contained therein, a driving shaft at the lower end of the vertical shaft, a universal joint connecting the shafts, and means for resiliently supporting the

vertical shaft for gyratory movement relative to the driving shaft during extracting whereby the receptacle may rotate about its center of mass.

HERBERT F. BARIFFI. 5
